KEY LEVER AND TYPE BAR MOUNTING FOR
TYPEWRITING MACHINES

Winifred M. Patton, Chicago, Ill.

Application October 13, 1950, Serial No. 190,006

5 Claims. (Cl. 197—27)

1

This invention relates to a novel construction of typewriter wherein the key lever and type bar mounting is materially simplified to substantially reduce the number of parts involved and to enable a typewriter to be very economically manufactured and sold.

More particularly, it is an aim of the present invention to provide a simplified typewriting structure which readily adapts itself for use in connection with all types of manually operated typewriters, particularly portable typewriters and toy typewriters.

Still a further object of the invention is to provide a typewriter structure which would be extremely efficient and durable for accomplishing its intended purpose and which is capable of being readily repaired or serviced.

Still a further object of the invention is to provide a novel key lever and type bar arrangement which will materially simplify the mounting of these parts and the housing or typewriter frame upon which the parts are supported.

Various other objects and advantages of the invention will hereinafter become more fully apparent from the following description of the drawing, illustrating a presently preferred embodiment thereof, and wherein:

Figure 1 is a fragmentary top plan view illustrating approximately one-half of a typewriting machine equipped with the invention;

Figure 2 is a vertical sectional view thereof taken substantially along a plane as indicated by the line 2—2 of Figure 1;

Figure 3 is a view similar to Figure 2 but showing the parts in a different position, and

Figure 4 is a fragmentary perspective view illustrating certain of the parts of the invention.

Referring more specifically to the drawing, 5 designates generally a portion only of a typewriter and constituting approximately one-half of the typewriting machine. Said typewriter 5 includes a base 6, only half of which is disclosed and which is adapted to be supported on any suitable horizontal supporting surface such as a desk or table. The rear portion of the base 6 is provided adjacent each end thereof with an upstanding bearing standard 7, only one of which has been illustrated and in which is journaled one end of the shaft 8 on which is mounted the usual platen 9, only one-half of which has been disclosed. The platen 9 and the parts associated therewith constitute no part of the present invention and have therefore not been illustrated in detail and have been partially shown only to indicate the movement of the keys, hereinafter to

2

be described, into and out of engagement with said platen.

The novel feature of the typewriting machine 5 relates to the key lever and type bar construction and mounting, designated generally 10. The front, arcuate edge 11 of the base 6 which is convexly bowed is provided adjacent each end thereof with an upstanding post 12, only one of which has been illustrated and a bar 13 is supported at its ends on the posts 12, said bar being secured to the posts 12 in any suitable manner. The bar 13 is likewise bowed outwardly with respect to the typewriter 5 from end-to-end thereof and is disposed above and substantially concentric to the front edge 11 of the base 6. Said bar 13 is provided between the posts 12 with a series of notches 14, as best illustrated in Figure 4, which are disposed perpendicular to the plane of the base 6 and which open outwardly of the upper edge of the bar 13. The bar 13 is also preferably provided with a bore 15 which extends longitudinally from end-to-end thereof through each of the notches 14 intermediate of their ends.

A rack bar 16, which is shorter than the bar 13 is supported above the base 6 by means of a pair of posts 17, only one of which has been illustrated, said bar 16 being disposed between the bar 13 and plate 9 and, like the bar 13, with its plane perpendicular to the plane of the base 6. Each end of the bar 16 is provided with a horizontally disposed apertured ear 18 which rests on one of the posts 17 and which is detachably secured thereto by a screw fastening 19 which extends downwardly through said ear and is detachably anchored in the post 17 disposed therebeneath.

The bar 16 is disposed substantially concentric to the bar 13 and is provided on its convex side, which faces the bar 13, with a series of longitudinally spaced transversely extending grooves 20. The bed of each groove 20 is provided with teeth forming a rack 21.

A key lever, designated generally 22, is pivotally mounted intermediate of its ends in each of the notches 14, each key lever 22, which comprises a rod, being provided with a flattened intermediate portion 23 which loosely fits into one of the notches 14 and which is provided with an opening to register with the bore 15. A single small rod 24 may extend longitudinally through the bore 15 from end-to-end of the bar 13 and loosely through the opening of each flattened lever portion 23 for mounting the individual levers 23 for selective rocking movement on the bar 13 or, if desired, two rods 24 may be provided each extending from an end of the bar 13

to a point intermediate of its ends or any other suitable pivotal mounting may be provided for pivotally supporting the lever portions 23 in the notches 14.

Each key lever 22 is provided with a substantially straight portion 25 which extends from the inner end of the intermediate lever portion 23 and from the inner concave side of the bar 13 downwardly and inwardly with respect to the bar 16 and base 6 and said portion 25 terminates in an upturned terminal portion 26 which has a flattened eye 27 at its terminal or free end. The opposite end portions of the levers 22, designated 28, extend from the opposite outer ends of the flattened intermediate lever portions 23 and outwardly with respect to the bar 13 and said lever portions 28 are of different lengths and are bent at different angles with respect to the lever portions 23 and 25 so that the lever ends 28 of the key levers 22 will all be disposed parallel and will be spaced different distances from the lever supporting bar 13 in order that the finger keys 29, supported on the terminals of the lever ends 28 will be staggered with respect to one another, as illustrated in Figure 1. Each lever end 28 is provided with an upturned terminal portion 30 on which a finger key 29 is secured. The number of levers 22 and finger keys 29 of the complete typewriting machine may vary, approximately one-half the total number having been illustrated in Figure 1.

The unit 10 also includes a plurality of type bars 31 corresponding in number to the key levers 22, notches 14 and grooves 20. Each type bar 31 has an angularly disposed extension or arm 32 at one end thereof which is disposed along a portion of one side of a key lever end 26 including its eye 27 and which is pivotally connected thereto by a pivot pin 33 which extends through said arm or extension 32 and through the eye 27. Each arm 32 is provided with teeth cut in the edge thereof forming a pinion segment 34, the teeth of which are disposed around the pivot pin 33. The teeth of the segment 34 may be spaced at slightly different distances from the axis of the pivot 33, for a purpose which will hereinafter become apparent. Each pinion segment 34 engages in one groove 20 and with certain of the teeth thereof meshing with certain of the teeth of the rack 21 of said groove. Each type bar 31 is provided with a type carrying head 35 on the outer side of its opposite, free end and the back edge of each type bar 31, adjacent its free end and opposite to the type head 35, is provided with an enlargement or rest 36 which is adapted to normally engage on the upper edge of the key lever bar 13, as illustrated in Figure 2. A contractile spring 37 is anchored to each key lever portion 25 and extends downwardly therefrom and away from said portion 25 and is anchored at its other end by an eye 38 to the base 6 near its arcuate front edge 11, so that the springs 37 tend to cause the levers 22 to swing clockwise on their pivots 24 to their positions of Figure 2 with the key supporting ends 30 of said levers elevated, as seen in Figure 2, and with the lever portions 25 and 26 disposed in a lowermost position and so that the type bars 31 will be positioned in retracted positions and with their portions 36 resting on the bar 13.

Assuming that the parts are thus positioned, as illustrated in Figure 2, by striking the individual keys 29 in a conventional manner, the lever 22 thereof will be rocked on its pivot 24 in

a clockwise direction as seen in Figures 2 and 3 from the position of the parts as shown in Figure 2 and for moving the parts to their positions of Figure 3. How this is accomplished is readily apparent, since as each lever portion 28, 30 is swung downwardly, the opposite end 25, 26 of said lever is swung upwardly and in moving upwardly carries the bar extension 32 connected thereto upwardly therewith. As said bar extension 32 has its pinion segment 34 meshing with its associated rack 21, as said extension 32 is displaced upwardly its pinion 34 will ride the rack 21 to cause the bar 32 to swing clockwise on the pivot 33 as its extension 32 moves upwardly so that when the key 29 of said lever 22 reached the depressed position of Figure 3 the type carrying head 35 of the bar 31 which is connected to said key lever will have swung clockwise on the pivot 33 through an arc sufficient so that the key carrying head 35 will have struck the platen 9. When pressure is released on the key 29, the spring 37 will rock the lever 22 clockwise back to its position of Figure 2 thereby exerting a downward pull on the extension 32 connected thereto as that the pinion segment thereof in moving down its associated rack portion 21 will cause its bar 31 to swing counterclockwise back to its position of Figure 2. The relatively deep grooves 20 function as guides to prevent any lateral displacement of the pinion segments 34 or the lever ends 26 or bar extensions 32. It will thus be seen that the type bars 31 are actually pivotally supported solely by the levers 22.

Various modifications and changes are contemplated and may obviously be resorted to, without departing from the spirit or scope of the invention as hereinafter defined by the appended claims.

I claim as my invention:

1. In a typewriting machine, a base, an arcuate key lever supporting bar disposed above a portion of said base, means for supporting said bar above the base, a plurality of key levers pivotally supported intermediate of their ends on said bar and spaced relatively to one another longitudinally of the bar, said levers each having an outer, key supporting end extending outwardly from the outer, convex side of the bar and an inner end including a portion extending normally downwardly and inwardly from the inner, concave side of said bar and having an upturned terminal portion, a type bar supported by each key lever having an angularly disposed extension at one end thereof pivotally connected to the free end of the upturned terminal portion of the inner end of the key lever, the edge of said bar extension around said pivot being toothed to provide a pinion segment, each type bar having an opposite type carrying free end, an arcuate rack bar disposed above said base inwardly of the key lever supporting bar and concentric thereto, and means for supporting the rack bar above the base, said rack bar having longitudinally spaced transversely extending grooves in its convex side forming guideways in which said pinion segments are movable, the bed portion of each groove being toothed to provide a rack for meshing engagement with the teeth of the pinion segment disposed in said groove.
2. A typewriting machine as in claim 1, and spring means connected to the base and last mentioned ends of the key levers for swinging

the last mentioned key lever ends downwardly on the key lever pivots.

3. A typewriting machine as in claim 1, said key lever supporting bar having longitudinally spaced notches for accommodating intermediate portions of the key levers and in which said intermediate portions are swingably disposed, and pivot means extending longitudinally through the key lever supporting bar and through said notches and intermediate lever portions and pivotally connecting the key levers to the key lever supporting bar.

4. A typewriting machine as in claim 1, each type bar having a rest adjacent its free end engaging on the key lever supporting bar when the type bar is in a retracted position, the pinion segment of each type bar being displaced upwardly of its rack and groove by the upward swinging movement of the inner end of the key lever connected thereto for causing said type bar to swing upwardly and out of engagement with the key lever supporting bar and over the upper edge of the rack bar.

5. In a typewriting machine, a plurality of key levers each pivotally mounted intermediate of the ends thereof and having an outer end and an inner type bar supporting end, a key fixed to and mounted on the outer end of each key lever, a type bar having an end pivotally connected to the inner type bar supporting end of each le-

ver, said type bar end having a pinion segment partially surrounding the pivotal connection of the key lever and type bar, and a stationary rack member having a rack portion in meshing engagement with and individual to each pinion segment whereby the opposite, free end of each type bar will be swung to a projected platen engaging position when the key lever, connected to said type bar, is rocked in one direction and returned to a retracted, inoperative position when said key lever is rocked in the opposite direction, said stationary rack member having grooves provided with bed portions defining said rack portions for guiding the pivotally connected ends of the key levers and type bars as the type bars are swung between projected and retracted position.
